Attorney, Agent, or Firm—Howrey & Simon

[57] **CLAIM**

The ornamental design for the vase or similar article, as shown and described.

DESCRIPTION

FIG. 1 is a top, front perspective view of a vase or similar article showing my new design, the bottom being flat and unornamented;

FIG. 2 is a side elevation view thereof; and

FIG. 3 is another side elevation view taken at a position approximately 45 degrees from the view depicted in FIG. 2 above.

FIG.1

FIG. 2

FIG. 3
